[57] CLAIM

The ornamental design for a sports shoe sole, as shown
and described.

DESCRIPTION

FIG. 1 is a bottom view of a sports shoe sole showing
my new design;

FIG. 2 is a side elevational view of the medial side
thereof;

FIG. 3 is a side elevational view of the lateral side
thereof;

FIG. 4 is a rear elevational view thereof; and,

FIG. 5 is a front elevational view thereof.

The top of the sole is plain.

FIG. 1

FIG. 2

FIG. 3

FIG. 4

FIG. 5
